JOSEPH A. HALEY, OF FORT WAYNE, INDIANA.

DUST-GUARD FOR JOURNAL-BOXES.

No. 830,062.

Specification of Letters Patent.

Patented Sept. 4, 1906.

Application filed February 20, 1905. Serial No. 246,599.

To all whom it may concern:

Be it known that I, JOSEPH A. HALEY, a citizen of the United States of America, residing at Fort Wayne, in the county of Allen and State of Indiana, have invented certain new and useful Improvements in Dust-Guards for Journal-Boxes; and I hereby declare the following to be a full, clear, and exact description of the invention, such as will enable others skilled in the art to which it pertains to make and use the same.

This invention relates to improvements in dust-guards for journal-boxes, and pertains more especially to a metal dust-guard contained within the rear or inner end of a journal-box and snugly embracing without clamping the axle, which extends into the box.

The primary object of this invention is to provide a dust-guard which is exceptionally long-lived and more effective in excluding dust and preventing waste of lubricant than dust-guards heretofore used.

Another object is to provide a dust-guard having a self-adjusting bearing for the axle without clamping the axle, with the said bearing preferably formed by two upright sliding pieces embracing the upper portion of the axle at opposite sides, respectively, of the axis of the axle and diverging upwardly from the axle, which bearing-forming pieces are arranged, therefore, externally and radially of the axle and have inwardly curved lower faces conforming to and extending circumferentially of the axle and mutually engage each other at the lower ends of their opposing surfaces, so that they lock each other as against displacement vertically independently of each other and lower together to take up wear between them and the axle.

Another object is to provide improved means for holding the dust-guard in place within the journal-box and maintain the forward or outer side or face of the dust-guard snugly against the forward or outer side wall of the dust-guard-containing chamber of the box.

With these objects in view and to the end of rendering the construction simple and durable and reliable in its operation and to the end of realizing other advantages hereinafter appearing this invention consists in certain features of construction and combinations of parts hereinafter described, and pointed out in the claims.

In the accompanying drawings, Figure 1 is a side elevation, largely in central longitudinal section, of a portion of a journal-box, and this figure also shows a side view of the end of an axle extending into the said box, with my improved dust-guard contained within the inner end of the box and extending around the axle. Fig. 2 is a transverse vertical section on line 2-2, Fig. 1, looking in the direction indicated by the arrow. Fig. 3 is a top plan in section on line 3-3, Fig. 2. Fig. 4 is a side elevation, partly in section, of the upper portion of the dust-guard detached. Fig. 5 is a section on line 5-5, Fig. 4, looking in the direction indicated by the arrow. Fig. 6 is a section on line 6-6, Fig. 4, looking downwardly. Figs. 3, 4, 5, and 6 are drawn on a larger scale than Figs. 1 and 2.

Referring to Figs. 1, 2, and 3 of the drawings, *a* indicates a journal-box, and *b* an axle, which extends into the said box in the usual manner. The box is provided within its rear or inner end with a quadrangular chamber *c*, which extends around the axle and is occupied by a correspondingly-shaped dust-guard, which comprises, preferably, a metal plate *d*, quadrangular in external contour and surrounding and snugly embracing the axle and contained within the chamber *c*. The plate *d* is provided centrally with a circular hole 10 to accommodate the location of the axle, which extends through the said hole. The plate *d* is arranged, preferably, next to the forward or outer side wall 12 of the chamber *c* and provided at the edges all round with reinforcing-flanges 13, which project endwise of the box toward the other side wall of the said chamber. The upper portion of the dust-guard detached is shown in Figs. 4, 5, and 6.

The forward or outer side wall 12 of the chamber *c* extends around the axle and is smooth and the forward or outer side or face of the plate *d* is held against the said wall and a dust-tight joint is formed between the plate and the wall.

Springs acting to retain the plate *d* against the wall 12 are provided and formed, preferably, by cutting and stamping portions 14 of the plate into the form of bow-springs which engage with and are held under tension by the rear or inner side wall 15 of the dust-guard-containing chamber. The springs 14 therefore effectually act to retain the dust-guard in position against the forward or outer side wall 12 of the said chamber. The

dust-guard illustrated is provided with four springs 14, arranged near the different corners, respectively, of the plate *d*.

My improved dust-guard snugly embraces 5 the axle without clamping the axle and is shown provided at the top of the axle with two upright companion and coöperating bearing-forming blocks or pieces *e*, which are arranged at opposite sides, respectively, of 10 the axis of the axle. The bearing-pieces *e* mutually engage each other at the lower ends of their opposing surfaces, as at *f*, and diverge upwardly. The bearing-pieces *e* are therefore arranged radially relative to the 15 axle and adjacent each other.

The bearing-pieces *e* are arranged also at a considerably lesser angle to each other than a right angle, so that they lock each other at their engaging ends to such an extent that 20 they cannot slide inwardly independently of each other. Obviously the mutually-engaging ends of the bearing-pieces *e* do not merely make contact with each other at a single point, but at a plurality of points along their 25 opposing surfaces, and arranged and locked together as described constitute means for preventing movement of the bearing formed by the said bearing-pieces *e* into clamping contact with the axle, and the provision of an 30 adjustable bearing which cannot possibly clamp the axle is of no inconsiderable importance.

Each bearing-piece *e* forms a slide which is arranged radially relative to the axle and engages and is slidable endwise of a correspondingly-arranged slideway which is formed, preferably, by two lugs or lips 16, formed by displacing portions of the plate *d* laterally of the plate. The said lips or lugs 16 embrace 40 or engage opposite side edges, respectively, of the said slide-forming bearing-piece.

The lower face of each bearing-piece *e* is hollowed out or curved inwardly and circumferentially of the axle to conform to the 45 axle and to render the said bearing-piece capable of snugly embracing the axle.

Each bearing-piece is provided centrally with a hole 17, arranged longitudinally of the bearing-piece, which hole is open at and extends a suitable distance downwardly from the top of the said piece, as shown in Figs. 4 and 5. A spiral spring *l* is seated within the said hole and extends above the said bearing-piece a suitable distance and at its upper end surrounds a lug 18, formed upon and depending from the top flange 13, which extends along the upper end of the plate *d*. The said spring acts to retain the said bearing-piece in its lower position, wherein it engages, as already indicated, with the companion bearing-piece. It will be observed, therefore, that the springs *l* act to retain the two companion bearing-pieces *e* in mutual engagement, that the lower faces of the said 65 bearing-pieces snugly embrace the upper

portion of the axle, that the said bearing-pieces coöperate in forming a self-adjusting bearing over the axle, and that they lock each other against vertical displacement independently of each other.

I would here remark that the two bearing-pieces *e* to insure their operation in unison are serrated or roughened, as at 20, upon their opposing edges, as shown in Fig. 4, with the teeth of the said edges meshing with each other at the lower ends of the said edges.

When the dust-guard is detached from the axle, the bearing-pieces *e* can be readily removed, if desired, for any reason by lifting them upon exerting pressure upwardly upon 80 their lower faces so as to unlock the bearing-pieces from each other and permitting one to lower while retaining pressure on the other.

It will be observed that a space 22 is formed between the opposing serrated edges of the 85 two bearing-pieces *e* and *e*, which space gradually increases in width toward its upper end; that the said space is closed at one side by the plate *d*, and that the said space is closed at its opposite side by a flange 23, formed upon and projecting from one of the bearing-pieces *e*; that the said space is closed at its upper end by a flange 24, formed upon and projecting from one of the bearing-pieces *e*; that the flanges 23 and 24 are preferably formed upon 95 one and the same bearing-piece *e* and perform the function of dust-guards in preventing the ingress of dust and dirt into the said space.

I would also remark that the plate *d* is provided at the side at which the bearing-pieces 10 *e* are located with a projecting flange *d*', extending along the surrounding wall of its opening 10 at the sides and bottom of the opening. The flange *d*' extends, preferably, from the outer side edge of one of the bearing-pieces *e* circumferentially of the adjacent side of the axle, thence in under the axle, and thence around the opposite side of the axle to the outer side edge of the other bearing-piece *e*. The flange *d*' snugly embraces the 110 axle from end to end without clamping the axle. The lower faces of the bearing-pieces *e* and the flange *d*' are arranged, therefore, to form a circular bearing which extends completely around the axle.

A not unimportant feature of my invention is the formation of the body portion of the dust-guard by a single sheet-metal plate having its forward side or face abutting against the forward or outer side wall of the dust-guard-containing chamber of the journal-box and having the flange *d*' and the bearing-pieces *e* snugly embracing the axle at the rear side of the said plate without clamping the axle at any point, so that wear upon the axle 125 and dust-guard, if not entirely avoided, is at least reduced to a minimum.

My improved dust-guard has been fully tested, and the tests to which it has been subjected have demonstrated that the dust- 130

guard, the axle-journal, and the bearing-affecting parts of the journal-box last much longer than with the use of dust-guards heretofore made and that waste of lubricant is effectually avoided.

What I claim is—

1. A dust-guard for a journal-box, said guard having an axle-accommodating opening and provided with a self-adjusting bearing which is arranged at the top and held externally of the opening and has means for preventing the movement of the said bearing into clamping contact with the axle.

2. A dust-guard for a journal-box, said guard comprising a metal plate having a centrally-located axle-accommodating opening, which plate is provided at the top of the opening with a self-adjusting bearing arranged to automatically lower to take up wear but always held over and externally of the axle-receiving space of the guard.

3. A dust-guard for a journal-box, said guard having an axle-accommodating opening and provided at the top with two bearing-pieces located externally of and diverging upwardly from the opening and movable together inwardly upon wear on their lower faces, said bearing-pieces mutually locking each other at the adjacent ends of their aforementioned faces and arranged at a considerable lesser angle to each other than a right angle, and means acting to simultaneously lower the said bearing-pieces.

4. A dust-guard for a journal-box, said guard having an axle-accommodating opening and comprising the following: two bearing-pieces arranged externally of and diverging from the said opening, which bearing-pieces mutually lock each other at their opposing surfaces, and have the said surfaces serrated or roughened, and means acting to retain the said bearing-pieces in contact with each other.

5. A dust-guard for a journal-box, said guard having an axle-accommodating opening and comprising the following: two upwardly-diverging suitably-guided bearing-pieces arranged at the top of the said openings which bearing-pieces mutually engage each other at the lower ends of their opposing surfaces and have the said surfaces serrated or roughened.

6. A dust-guard for a journal-box, said guard having a body portion which is provided with an axle-accommodating opening; and two bearing-pieces arranged externally of and diverging from the said opening, said bearing-pieces mutually engaging each other at their adjacent ends, and the body portion having members overlapping the side edges of and guiding the bearing-pieces.

7. A dust-guard for a journal-box, said guard comprising a plate which has an axle-accommodating opening, and two bearing-pieces arranged externally of and diverging

from the said opening, said bearing-pieces mutually engaging each other, and there being lugs formed on the aforesaid plate and overlapping the side edges of and guiding the bearing-pieces.

8. A dust-guard for a journal-box, said guard comprising a plate which has an axle-accommodating opening; two upwardly-diverging bearing-pieces arranged at the top of the said opening and having lower faces arranged circumferentially of the said opening, said bearing-pieces mutually engaging each other, and lugs formed on the aforesaid plate and overlapping the side edges of and guiding the bearing-pieces.

9. A dust-guard for a journal-box, said guard comprising a plate which has an axle-accommodating opening; two upwardly-diverging bearing-pieces arranged at one side of the plate and at the top of the said opening and locked to each other but free to lower together to take up wear upon their lower faces, spiral springs seated in and extending from within the bearing-pieces, there being a flange formed on and at the top of the aforesaid plate, and a connection between the springs and the said flange.

10. A dust-guard for a journal-box, said guard having an axle-accommodating opening and provided with a self-adjusting bearing which is formed only by two bearing-pieces which are arranged at a considerably lesser angle to each other than a right angle at the top of the said opening and always held externally of the axle-receiving space of the guard, said bearing-pieces automatically locking each other and only free to lower together to take up wear, and means acting to retain the said bearing-pieces in contact with each other.

11. A dust-guard for a journal-box, said guard having an axle-accommodating opening and provided with a self-adjusting bearing formed by two upwardly-diverging bearing-pieces arranged at the top of the said opening and locked to each other but free to lower together to take up wear upon their lower faces, with the opposing surfaces of the said bearing-pieces next above their said faces serrated or roughened, and means for preventing the ingress of dust or dirt into the space between the opposing serrated or roughened surfaces of the bearing-pieces.

12. A dust-guard for a journal-box, said guard comprising a body portion having an axle-accommodating opening and provided with two suitably-guided upwardly-diverging bearing-pieces arranged at the top of the aforesaid opening, said bearing-pieces mutually engaging each other at the lower ends of their opposing surfaces and having the said surfaces serrated or roughened, and means for excluding dust and dirt from the space between the aforesaid surfaces.

13. A dust-guard for a journal-box, said

4
guard comprising a body portion having an axle-accommodating opening and provided, at one side of the body portion, with two upwardly-diverging suitably-guided bearing-
5 pieces arranged at the top of the aforesaid opening, said bearing-pieces mutually engaging each other at the lower ends of their opposing surfaces, there being a flange formed on one of the said bearing-pieces at and covering the space between the aforesaid surfaces.

10 14. A dust-guard for a journal-box, said guard comprising a body portion having an axle-accommodating opening and provided, at one side of the body portion, with two upwardly-diverging suitably-guided bearing-
15 pieces arranged at the top of the aforesaid opening, said bearing-pieces mutually engaging each other at the lower ends of their opposing surfaces; and one of the bearing-pieces
20

having two flanges arranged to exclude dust and dirt from the space between the aforesaid surfaces at the top and rear side respectively of the space.

15. A dust-guard for a journal-box, said 25 guard comprising a body portion having an axle-accommodating opening and provided with two suitably-guided bearing-pieces arranged next externally of and diverging from the aforesaid opening, said bearing-pieces 30 mutually engaging each other at the adjacent ends of their opposing surfaces, there being means for excluding dust and dirt from the space between the aforesaid surfaces.

In testimony whereof I sign the foregoing 35 specification in the presence of two witnesses.

JOSEPH A. HALEY.
